OR

D 13,411

EX

No. 13,411

Nov. 14, 1882

UNITED STATES PATENT OFFICE.

JOHN L. POPE, OF CLEVELAND, OHIO.

DESIGN FOR A WEAR-IRON.

SPECIFICATION forming part of Design No. 13,411, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Wear Irons, of which the following is a specification, reference being had to the engraving forming part thereof.

My present invention relates to a novel design for wear-irons applied to carriages and other vehicles; and it consists in certain features of ornamentation and configuration which will be hereinafter more particularly set forth and claimed.

In the accompanying engraving the wear-iron is shown as provided with two ear-pieces or lugs, *a a*, that have holes in them, through which the usual fastening devices are inserted for the purpose of securing the article to the body or other portion of the vehicle. The main portion of the iron is ornamented on its upper or outer face by two ribs or "swells," that I have designated by the letters *b* and *c*, respectively, and between which the metal of the "iron" has a sunken or depressed appearance. I have improved the shape of the article by contracting the metal at those points where the shank or main portion of the iron runs into the two short ends cast or bent at

about right angles thereto, and which contracted or narrowed parts will be found where I have placed the reference-letters *e e*. These contractions in the width of the iron are formed by running the inner bead, *c*, outward obliquely from where it leaves either of the lugs *a a*. Between the contractions just referred to the shank of the iron along its under or lower edge is gradually bowed or bellied, making the shank wider along the line *x x*.

What I claim as of my invention, and desire to secure by Letters Patent, is—

1. A wear-iron ornamented with two ribs, *b* and *c*, substantially as shown and described.

2. A wear-iron having the ornamental bead *c* running obliquely outward from either of the lugs *a*, substantially as shown and described.

3. A wear-iron having the bead or rib *c* bowed along the shank of the iron, substantially as shown and described.

In testimony whereof I have hereunto set my hand this 22d day of June, 1882.

JOHN L. POPE.

In presence of—

CHAS. W. MOSES,
C. M. COPP.
